LAMP FILAMENT MOUNT

Roland D. Eaton, Huntington Park, Calif., assignor to Technicolor Motion Picture Corporation, Hollywood, Calif., a corporation of Maine

Application November 2, 1948, Serial No. 57,875

12 Claims. (Cl. 176—40)

1

This invention relates to supports for mounting a ribbon filament in lamps such as stroboscopic and cinematographic printing lamps where it is desirable to produce a high light intensity which may be changed quickly. Ribbon filaments having fast heating and cooling rates are commonly selected for such a use. Hitherto the filament has been rigidly clamped or welded to a support mounted on the base or dish of the lamp. However, the life of filament so supported is very short owing to mechanical and thermal stresses which cause the filament to crinkle a short distance from the support and finally burn out at the crinkle boundary furthest from the support. Expansion of the filament between its rigidly fixed ends is partially responsible for the mechanical stress. Temperature gradients along the filament also contribute to the crinkling.

Objects of the present invention are to provide a way of mounting the filament so as to maintain a uniform temperature throughout its length with no sharp temperature gradients present in the mount near the filament, and to prevent crinkling of the filament as a result of thermal expansion. A further object is to provide a mount which is simple and durable in structure and economical to manufacture.

In one aspect the invention comprises a device for mounting a ribbon filament on a lamp base involving the combination of a pair of opposed spring leaves one end of which grips the filament resiliently throughout a considerable area, attached to the base a support for the leaves near the other end thereof, and means for clamping the springs on the support, characterized in that the conductivity from the springs to the support is less than that from the filament to the springs. The term conductivity is used herein to refer primarily to thermal conductivity.

In another aspect the gripping end of the filament is spaced from the support, and intermediate portions of the springs bridge the space, the conductivity from the springs to the support being less than that in the intermediate portions. Preferably the conductivity from the springs to the support is less than either that in the intermediate portions or that from the filament to the springs.

In another aspect an element is interposed between the supported ends of each of the springs and the support, the element having a conductivity less than that from the filament to the springs and less than that of the springs. Preferably the area of contact between the springs and the support is less than the gripping area of

2

the springs or the cross-sectional area of the intermediate portions of the springs.

In a still further aspect the invention comprises the combination of a pair of opposed leaf springs for gripping the filament resiliently therebetween throughout a considerable area near one end of the springs, and a support for the leaves near the other end thereof, said first ends of the springs curving away from the filament.

10 For the purpose of illustration a typical embodiment of the invention is shown in the drawings in which:

Fig. 1 is an elevation of the lamp with part of the glass envelope broken away;

15 Fig. 2 is an enlarged isometric view of the lamp, parts being broken away;

Fig. 3 is an exploded isometric view of the filament support; and

Fig. 4 is a top view of the filament support.

20 As shown in Figs. 1 and 2 the lamp comprises an insulating base 1 to which is secured a glass envelope 2 and copper thimbles 3. Press fitted within the thimbles are nickel studs 4 which are slotted at the upper ends. Within each of the 25 slots 11 is clamped a pair of molybdenum leaf springs 6, and loosely gripped between the springs is the tungsten filament 7. In operation electrical current passes in one of the thimbles, through a stud to the clamps, thence through the filament to the opposite clamps, and thence through the stud to the thimble.

In Fig. 3 the filament and the supporting parts are shown in approximately three-quarters actual size. The tungsten filament is approximately one and one half inches long, three-quarters inch wide and 0.001 inch thick. The width of the leaf springs 6 is the same as that of the filament. Preferably the slot in the nickel studs is about twice as long as the filament is wide, the walls of the slot being machined to allow flat contact on nickel sheet blocks 8 which are mounted at one end of the springs 6. The nickel stud may be blackened to promote heat-dissipation and copper cooling fins may be added to the portion below the slot to further cool the stud. The bifurcated portions of the stud are urged together by stainless steel machine screws 12.

The block 8 is approximately one-quarter as long as the width of the clamp and about one-sixteenth of an inch wide. It may be cut from a .005 inch nickel sheet block. These blocks are tightly clamped between the walls of the slot and the leaf springs. Preferably they are welded to the leaf springs. The blocks, owing to their 50 lower conductivity and the small area of contact

between the blocks and the studs, serve as thermal and electrical resistance. Without the blocks the studs being cooler than the springs, would tend to cool the springs, creating sharp temperature gradients at or near the clamping ends of the springs and causing thermal distortions such as crinkling in the springs. However, when elements of low conductance, such as the blocks, are interposed between the springs and the post, owing to their high electrical resistance such elements heat up and serve to insulate the springs thermally from the post. Throughout their length the springs remain at an almost constant temperature, orange hot, and temperature dropping occurs in the stud near the area of contact with the blocks.

Near the opposite ends of the springs from the blocks the filament is resiliently gripped between two parallel flat surfaces 14 of the springs. This gripping is loose enough so that the filament may be moved by direct force, but not loose enough so that it may be shaken out of the springs. The filament is gripped throughout an area having the width of the filament and approximately one-third that length. This contact has sufficient conductivity to prevent excessive temperature drop thereat thereby avoiding excessive temperature gradients in the filament and therefore minimizing local thermal distortions. The loose gripping action of the clamps allows the filament to expand evenly throughout its length and thus prevents mechanical stresses from developing.

The ends of the springs 16 are curved away from the filament so that the end of the gripping area of the springs have no burrs or other irregularities which would damage the filament. Furthermore the curved ends 16 prevent warping in the flat portions of the springs and thermal crinkles which would also damage the filament and reduce its life.

As shown in Fig. 4 a short intermediate portion 15 of the springs bridges a space between the clamped portion 13 of the springs and the gripping portion 14 for the purpose of spacing the filament a short distance from the clamped ends of the springs so that distortions near the portions clamped between the two blocks will not affect the filament.

Filaments mounted in this way have been found to have a life double that of filaments mounted in the old way. By use of the leaf springs the physical length of the high resistance filament may be shortened thus saving material and electrical power.

It should be understood that the present disclosure is for the purpose of illustration only and that this invention includes all modifications and equivalents which fall within the scope of the appended claims.

I claim:

1. For mounting a ribbon filament on a lamp base, the combination of a pair of opposed leaf springs for gripping the filament resiliently therebetween throughout a considerable area near one end of the springs, attached to the base a support for the springs near the other end thereof, and means for clamping the springs on the support, the conductivity from the springs to the support being less than that from the filament to the springs.

2. For mounting a ribbon filament on a lamp base, the combination of a pair of opposed leaves for gripping the filament resiliently therebetween near one end of the springs, attached to the base a support for the springs near the other end

thereof, the end of the filament being spaced from the support with intermediate portions of the springs bridging the space, and means for clamping the springs on the support, the conductivity from the springs to the support being less than that in said portions.

3. For mounting a ribbon filament on a lamp base, the combination of a pair of opposed leaf springs for gripping the filament resiliently therebetween throughout a considerable area near one end of the springs, attached to the base a support for the springs near the other end thereof, the end of the filament being spaced from the support with intermediate portions of the leaves bridging the space, and means for clamping the springs on the support, the conductivity from the springs to the support being less than that from the filament to the springs and that in said portions.

4. For mounting a ribbon filament on a lamp base, the combination of a pair of opposed leaf springs for gripping the filament resiliently therebetween throughout a considerable area near one end of the springs, attached to the base a support for the springs near the other end thereof, and an element between the support and said other end of conductivity lower than that from the filament to the springs.

5. For mounting a ribbon filament on a lamp base, the combination of a pair of opposed leaf springs for gripping the filament resiliently therebetween near one end of the springs, and attached to the base a support for the springs near the other end thereof, the end of the filament being spaced from the support with intermediate portions of the springs bridging the space, and an element between the support and said other end of conductivity lower than that of the intermediate portions.

6. For mounting a ribbon filament on a lamp base, the combination of a pair of opposed leaves for gripping the filament resiliently therebetween throughout a considerable area near one end of the leaf springs, attached to the base a support for the springs near the other end thereof, the end of the filament being spaced from the support with intermediate portions of the leaves bridging the space, and an element between the support and said other end of conductivity lower than that of the intermediate portions and that from the filament to the springs.

7. For mounting a ribbon filament on a lamp base, the combination of a pair of opposed leaf springs for gripping the filament resiliently therebetween throughout a considerable area near one end of the springs and attached to the base a support for the leaves near the other end thereof, the area of contact between the leaves and the support being less than the first said area.

8. For mounting a ribbon filament on a lamp base, the combination of a pair of opposed leaves for gripping the filament resiliently therebetween near one end of the leaf springs, and attached to the base a support for the springs near the other end thereof, the end of the filament being spaced from the support with the intermediate portions of the leaves bridging the space, the area of contact between the leaves and the support being less than the cross-sectional area of said portions.

9. For mounting a ribbon filament on a lamp base the combination of a pair of opposed leaf springs for gripping the filament resiliently therebetween throughout a considerable area

near one end of the springs, and attached to the base a support for the springs near the other end thereof, the end of the filament being spaced from the support throughout a gap with the intermediate portions of the leaves bridging the gap, the area of contact between the leaves and the support being less than the cross-sectional area of said portions and than that of the first said area.

10. For mounting a ribbon filament on a lamp base, the combination of a pair of clamps mounted on the base in spaced relation, a pair of leaf springs held rigidly by each of the clamps, said springs having mutually contacting surfaces at one end, and parallel surfaces near the other end for gripping one end of the filament resiliently throughout a considerable area, and an element between the first said ends and the clamp of lower conductivity than that of said springs and that from the filament to the springs, whereby distortion of the filament and springs as they expand when heated may be prevented and a uniform temperature may be maintained throughout the length of the filament.

11. For mounting a ribbon filament on a lamp base, the combination of a pair of opposed leaf springs for gripping the filament resiliently therebetween throughout a considerable area near one end of the springs and attached to the base a support for the leaves near the other end thereof, said one end having a surface curved away from the filament.

12. For mounting a ribbon filament on a lamp base, the combination of a pair of clamps mounted on the base in spaced relation, a pair of leaf springs held rigidly by each of the clamps, said springs having mutually contacting surfaces at a first end, surfaces curved away from each other at the other end, flat parallel surfaces adjacent said curved surfaces for gripping one end of the filament, intermediate portions between the contacting surfaces and the parallel surfaces, and an element carried on each of said first ends having one surface in contact with the clamp, said element being of conductivity lower than that of the springs and than that from the filament to the springs, whereby distortion of the filament and the springs as they expand when heated may be prevented and a uniform temperature may be maintained throughout the length of the filament.
